Attorney

UNITED STATES PATENT OFFICE.

SHICHIGORO KUNO, OF SUBLLET, WYOMING.

COVER-LIFTING DEVICE.

Application filed September 26, 1921. Serial No. 503,132.

To all whom it may concern:

Be it known that I, SHICHIGORO KUNO, a subject of the Emperor of Japan, residing at Sublet, county of Lincoln, and State of Wyoming, have invented certain new and useful Improvements in Cover - Lifting Devices; and I do declare the following to be a full, clear, and exact description of the invention, such as will enable others skilled in the art 10 to which it appertains to make and use the same, reference being had to the accompanying drawings, and to the characters of reference marked thereon, which form a part of my application, Serial No. 503,132, filed 15 September 26, 1921.

This invention relates to water closets and has special reference to means for opening and closing the cover without employing the hands therefor.

20 It is often necessary to raise the covers on toilet stands when the hands are otherwise occupied, and it is the object of this invention to provide a device which permits the operator to raise and lower the cover by 25 means of his feet. Another object of my invention is to so correlate the various parts that the cover will not close with a sudden "bang" but will reach its lowered position gently. It is also my object to devise a 30 means for the purpose pointed out above, that shall be of a strong and substantial construction, neat in appearance and which can be cheaply constructed.

In order to more clearly describe my invention, I shall have reference to the accompanying drawing in which—

Fig. 1 shows my device attached to the cover of a water closet stand and shows the cover in its lowered position; and

40 Fig. 2 shows the cover in raised position.

The same reference characters refer to the same parts in the different views.

Numeral 1 represents a toilet fixture of ordinary construction which may be provided with an elevated tank or a low flush tank 2. A cover 3 is attached to the stand in the usual manner by means of hinges 4. My improved cover lifting device, which I have indicated as a whole by reference numeral 5, comprises a support 6 which is adapted to be secured to the floor by means of screws or bolts (not shown) and is provided with two spaced upright members 7 between which is mounted a curved lever 8 which is connected to the upright members

by means of a pivot 9. One end of lever 8 is provided with a pedal 10 which is adapted to receive pressure from the application of a person's foot for the purpose of rotating the lever about pivot 9. A second slightly curved lever 11 is pivotally attached at 12 to one end of lever 8 and has its upper end connected to a plate 13 by means of a pivot pin 14. It is evident that with levers 8 and 11 connected to each other and pivoted to the floor and the cover in the manner pointed out, that when pedal 10 is pressed downwardly and rotates bar 8 about pivot 9, lever 11 will move the cover 3 upwardly and turn it on its hinges 4. If I employed only 70 levers 8 and 11, the cover 3 would fall back to its lowered position with a "bang" which would soon cause it to break. In order to insure a noiseless and a harmless return of cover 3, I provide lever 11 with a longitudinal slot 15, within which moves a pin 16. A third slightly curved member 17 is pivotally connected to lever 8 at point 18 and the other end is slidably and pivotally connected to slot 15 by means of pin 16. It is evident that as lever 8 is rotated about its pivot 9, member 17 will rotate on pivot 18 and cause pin 16 to slide in slot 15. In order to provide a spring buffer action as the cover reaches its normal or lowered position, I 75 provide two springs 19 and 20, which have their ends non-rotatably connected to the levers. Spring 19 is bowed downwardly and spring 20 is bowed upwardly. The action of the particular combination of levers and 80 springs shown is that as the cover approaches its normal position, the springs exert a buffer action which prevents the cover from striking the top of the fixture with a slamming action. When the cover is 85 partially elevated, the springs have very little or no effect, but as the cover approaches its upper limit, the springs offer a slight resistance which serves to start the cover moving towards its normal position whenever 90 pressure is removed from the pedal 10.

The above described action is due to the fact that the springs 19 and 20 are so related to the arms 8, 11 and 17 that if these are free to move, they will assume a position of equilibrium at a point intermediate that shown in Fig. 1 and in Fig. 2. A movement of the cover from the position in which the arms and spring are in equilibrium to the closed position will cause the springs 110

19 and 20 to engage each other with considerable force and to subject them to flexure. This flexure acts as a cushion to prevent the cover from slamming. When the cover is 5 raised to the position shown in Fig. 2, the springs are bent substantially as shown, and this produces a force tending to close the cover. By having the parts so related that a point of equilibrium exists when the cover 10 is in some intermediate position, the action above described will result.

From the above it will appear that I have provided a simple, effective and conveniently operated device for raising and lowering the 15 cover on a toilet fixture by merely pressing down upon a conveniently operated pedal.

Having now described my invention or discovery, what I claim as new is—

1. In combination, a toilet fixture, a cover 20 hingedly connected thereto, a stationary pivot, a lever mounted on said pivot and adapted to rock thereon, a second lever having one end pivotally connected to the cover and the other end pivotally connected to one end of the first named lever, the other end 25 thereof being provided with a pedal, said second lever having a longitudinal slot between its ends, a third lever pivoted to the first lever and provided with a pin for slidably engaging in said slot, and spring means connecting the third lever with each 30 of the other two levers, and adapted to modify the action of said levers.

2. In combination, a toilet fixture, a cover hingedly connected thereto, a stationary pivot, a lever mounted on said pivot and adapted to rock thereon, a second lever having one end pivotally connected to the cover and the other end pivotally connected to one end of the first named lever, the other end 35 thereof being provided with a pedal, said second lever having a longitudinal slot between its ends, a third lever pivoted to the first lever and provided with a pin for slidably engaging in said slot, and spring means connecting the third lever with each 40 of the other two levers, and adapted to modify the action of said levers.

3. In combination, a toilet fixture, a cover hingedly connected thereto, means for opening and closing said cover, said means comprising a stationary pivot, a curved lever mounted on said pivot and adapted to rock thereon, a second curved lever pivotally connected to the cover and to one end of said first named lever, said second lever having 50 an elongated slot between its ends, a third curved lever pivotally connected to said first lever and having means for slidably engaging in the slot of the second member, and spring means which serve as a buffer at the 55 opening and closing of said cover.

In testimony whereof I affix my signature.

SHICHIGORO KUNO.
